2,329,233

FILLER FEEDING CHANNEL CONSTRUCTION

Henry H. Wheeler, Brooklyn, N. Y., assignor to
International Cigar Machinery Company, a
corporation of New Jersey

Original application June 8, 1937, Serial No.
147,022. Divided and this application August
9, 1941, Serial No. 406,105

3 Claims. (Cl. 131—84)

This invention relates to filler feeds for cigar machines and more particularly to the cross feeds thereof. This application is a division of my co-pending application, Serial No. 147,022, filed June 8, 1937, on which my Patent 2,276,361 was issued March 17, 1942, and the subject matter of the present application pertains to the construction of the filler feeding channel, and one of the objects of the invention is to provide a filler feeding channel of novel construction.

The side belts of the present filler feeding channel have vertical runs which are more widely spaced apart along the section at which the filler tobacco is deposited therebetween than at the opposed vertical runs of the side belts at the forward or delivery end of the channel from which the stream of tobacco is advanced under the bunch length cutter. Thus with an automatic leaf feed for depositing the filler tobacco between the side belts of the filler feeding channel, as shown in the particular embodiment of the invention illustrated herein, there is more room in which to deposit the filler tobacco between said more widely spaced vertical runs of the side belts; and the stream of filler tobacco so formed may be constricted between the more closely spaced vertical runs at the delivery end of the channel to a width corresponding to the desired width of the bunch length. Heretofore the side walls of the filler feeding channel of the cross feed comprised parallel opposed vertical runs of the filler feeding belts, and when a very thin filler stream was advanced in the channel for severance of bunch lengths the presence of any shallow portions in the stream due to inaccuracies in laying the filler tobacco in the channel would result in substantial inaccuracies in the volume of the bunch length severed from the stream.

With this and other objects not specifically mentioned in view, the invention consists in certain constructions and combinations hereinafter fully described and specifically set forth in the claims hereunto appended.

Referring to the drawings which form a part of this specification and wherein like characters of reference indicate the same or like parts:

Fig. 1 is a plan view of the improved filler feeding channel;

Fig. 2 is a cross-section thereof showing the drive for the filler feeding belts;

Fig. 3 is a side elevation of the clutch mechanism controlling the operation of the cross feed;

Fig. 4 is a side elevation showing the connec-

tion of the cross feed drive to the clutch mechanism and the main drive; and

Fig. 5 is a longitudinal section of a portion of the filler channel, the compression foot and the bunch length cutter.

Referring to Fig. 4 of the drawings, a frame 11 supports a series of filler feed chains 12, which have a construction similar to that shown in my above mentioned application and carry impaling pins and travel over sprockets mounted on the drive shaft 16 and sprockets 17 mounted on shaft 18 (Fig. 4). The shaft 16 is driven from drive means controlled by the tobacco measuring and forwarding mechanism hereinafter described.

The hopper 19, which is provided with a cover 20 to keep the tobacco from drying out too rapidly, has a rear wall indicated generally at 23 and is arranged to hold a supply of long filler tobacco. The pins on the chains impale or engage the filler leaves in the supply in the hopper and carry them upwardly. The leaves are stripped from the pins at the delivery point by members (not shown) and fall into an elongated chamber (not shown) from which the leaves are delivered to a scale pan (not shown). The scale beam shaft 42 (Fig. 3) is provided with a cam 47 which supports a roller 48 connected by pin 48a to a vertical rod 49 reciprocable between two sets of guide rolls 50 and connected at its upper end to a cam lever 51 by a link 49a. This cam lever 51 is lifted at intervals by a continuously rotating cam 55 loosely mounted on the shaft 16 and secured to sprocket 52, in order to permit over-balancing of the scale pan by releasing pressure on the cam 47 and allow the raised portion 47a of the cam 47 to be rotated from under the roller 48. Rotation of cam 55, as will be hereinafter described, trips a pawl 63 and permits the pawl to engage the ratchet teeth 62a thereby stopping the rotation of disk 62 (Fig. 3) of a clutch 34 (Fig. 4) having a construction similar to that shown in Patent 2,124,219. This serves to disengage the clutch, as is clearly shown from the disclosure set forth in Patent 2,124,219, permitting the shaft to stop and the feeding of the long filler leaves to terminate.

Thus when the depressed or cutout portion 54 of the cam 55 reaches the cam roller 53 the lever 51 through the link 49a and plunger 49 pushes the cam 47, causing the same to rotate the shaft 42 and scale beam 41b still farther downwardly, depressing the scale pan and thereby opening gates (not shown) on the bottom of the scale pan. This permits the leaves on the pan to drop

downwardly to the cross feed. A spring 57 anchored at 58 on the lever 51 and suitably attached to frame 11 maintains the roller 53 in engagement with the cam 55.

The declutching of clutch 34 to stop the automatic filler feed is caused as follows:

An extension 51a on the lever 51 engages an adjacent screw 59 secured to the lever 60 on the pivot pin 61 suitably mounted on the frame of the machine. Thus when the lever 51 is permitted by the cam 47 to lower into the cutout 54 of the cam 55, extension 51a on said lever is lifted, thereby pushing up said screw 59 and lifting lever 60 together with latch piece 60a, thus permitting the ratchet lever 63, urged by spring 63b, to drop into engagement with the teeth 62a of disk 62 of the clutch 34 to declutch shaft 16 from the drive sprocket 52 which is connected to the main drive of the machine, causing the shaft and the feed mechanism connected thereto to stop. The ratchet wheel 62 is loosely mounted on the shaft 16 and is provided with suitable control prongs which operate rollers which form the driving connection between an outer flange of the clutch 34 connected to the sprocket 52, which is driven from the main drive of the cigar machine, and an inner driving disk which is keyed to the shaft 16, the arrangement of these parts being similar to that of Patent 2,124,219 above referred to.

Once the clutch 34 has been declutched, feeding of the long filler tobacco leaves ceases. Thereafter the clutch will remain declutched and there will be no feeding so long as there is sufficiency of tobacco for forming charges at the main feed of the cigar machine. When however the supply of tobacco at this point gets below normal, the feeding is restarted and the cross feed also starts. The means for accomplishing this result is shown in Fig. 3. It consists of a link 64 connected at 65 to the pawl 63 and having an elongated slot which is engaged by a pin 66 of a lever 67a, the lever being secured to a rake shaft 67 which supports the rake 67b acting to sweep the tobacco cut from the forward end of the cross feed into the column of tobacco from which the charge is cut. As will be seen from Fig. 3, if on the forward movement of the rake 67b it encounters a mass of tobacco in the column of tobacco ahead of the same, such that the rake can move only a limited distance, then the rake will not operate to disengage the pawl 63 from the ratchet teeth 62 and the feeding will not start, there being already enough tobacco available. If however the rake moves well forward then the pin reaches the end of the slot 66a and pushes the pawl out of engagement with the ratchet teeth. At the same time this relatches the latch 60a and latch piece 63a until such time as the over-balancing of the scale pan stops the feeding operation again. When the pawl 63 is withdrawn from the ratchet wheel 62a driving of the shaft 16 is resumed and feeding of the long filler tobacco leaves restarts. It may be stated that the construction of the rake and cross feed and main feed is generally similar to that shown in Patent 1,740,571 to W. B. Bronander issued December 24, 1929, to which reference is made for details of the construction. As clearly set forth in said patent the intermittent feeding cycle of the cross feed also is omitted when the rake encounters a surplus of tobacco and is restarted when the rake encounters an insufficiency.

Accordingly when a sufficient weight of leaves

of filler tobacco has fallen into the scale pan, the leaves are delivered between the raised gates 68a and 68b constituting a cover, and when open, forming a chute into the filler feeding channel 69 of the cross feed mechanism. The gates 68a and 68b when closed form a cover to hold down the ends of the longitudinally extending leaves in said channel. For the purpose of opening the cross feed cover gates 68a and 68b, lever arms 71 and 72 secured to said gates are provided and operated by a rack 73 and pinions 74 from cam lever 75. The latter is provided with a cam roller 117 engaging a cam 115 mounted on a shaft 116 driven by a chain 118 from a sprocket on shaft 100 and thereby actuated in timed relation to the operation of the long filler feed mechanism and cross feed so that these gates are maintained in open position when tobacco is delivered from the scale pan and in closed position during the intermediate forward motion of the bottom belt 76 and the side belts 77 of the cross feed.

At the forward end of the cross feed, as shown in Fig. 1, there is provided a vertically reciprocating plunger 78a carrying a corrugated knife 78 which serves to cut from the length of tobacco advanced by the cross feed a bunch length section of tobacco which is supported on a swingable shelf 80 (Fig. 3) during the cutting operation. After the length has been cut, the shelf, together with an overlying lever 81 is swung downwardly to a position where the rake may sweep a cut length from said shelf on to main feed belt 82 and into association with the tobacco column C which is forwarded by said main feed through movement of said belt 82 and a star wheel 83. This column is thus forwarded under the knife 84 which periodically cuts charges sufficient for one bunch from the column which charges are then delivered by a bunch charge transfer (not shown) into the rolling apron where the cigar bunch is formed.

It is noted that inasmuch as the cross feed is controlled by the operation of the rake 67b and the starting of the feeding operation of the long filler leaves is also controlled by said rake the two will be operated in proper timed relation. The cross feed will be open and ready to receive the leaves delivered by the scale pan when the scale pan is in operation to deliver the same.

The leaves dropped into the scale pan overbalance the arm of the scale. When the raised portion 41a of the cam 47 swings out from under the cam follower 48, the pressure of the cam follower on the upwardly inclined cam surface 47 forces the scale pan down the rest of the way. The scale pan is balanced by a suitable weight 41a which is adjustable radially on a threaded arm 41b on the scale shaft 42. Since the weight of the cam follower 49 and the pressure produced by the spring 57 will hold the delicately balanced scale arm 41a, 41b against rotation, it is important that this can be periodically released; and this is done by providing the continuously rotating cam member 55 with a series of depressions 55a into which the follower 53 drops periodically. Thus the raised portion between the depressions lifts the cam follower and releases the cam; yet as long as the cam follower on its downward movement feels the raised portion 41a, no change in the feeding cycle occurs. When however the raised portion of the cam 47 passes from under the cam follower 48 and the scale pan is depressed, nothing holds the lever 51 in upward position except the cam

55 and when the cutout portion 54 thereof is reached, the lever drops, terminating the operating cycle of the automatic filler feed through rotation of shaft 46, as already described. The lifting of the ratchet lever 63 starts the feeding cycle through the relatching of the latch 60a and the latch piece 63a to hold the ratchet 63 out of declutching or drive stopping position on the disk 62.

It is noted that even though the return of the scale pan after dumping of the leaves through overbalancing of the same by the weight 41a, otherwise places the machine in condition for restarting the feeding motion of the parts, feeding will not be started until the rake 67b lifts the latch 63. This is because lifting of the cam follower 48a and lever 51, and in consequence the lowering of the latch pieces 60 is insufficient to hold the ratchet 63 out of drive stopping position until such ratchet is lifted through link 64 by the rake 67b encountering an insufficiency of tobacco in the column C. Since the rake 67b also controls the operation of the cross feed, the two will be started in timed relation so that the cross feed and the automatic long filler feeding devices will operate in proper synchronism.

In connection with the cross feed generally indicated at F in Fig. 1, it will be noted that it consists of three endless belts, the operative runs 77a and 78 of which form a channel into which the tobacco leaves are deposited. As shown in Fig. 2, the belts 77 are driven by pulleys 87 and 88 on shafts 89 and 90 respectively which are driven in turn through bevel gears 91 and 92, and thence by gears 93 and 94 through shaft 95 and sprocket 97. The latter is driven by chain 111 from a sprocket 110 (Fig. 4) mounted on shaft 109 driven through bevel gears 108 from shaft 107. The belt 76 is driven by a pulley on shaft 95 as shown in Fig. 2. As disclosed in Patent 1,740,571, the cross feed is driven through a crank 103a on shaft 102 and connected by a rod 103 to an arm 104 loosely mounted on shaft 107 and carrying a pawl 105 which may be tripped into engagement with a ratchet 113 fastened on shaft 101, by a pivoted finger connected by a link 112 to rake 67b. Thus when the rake encounters an insufficiency of filler tobacco in the column it will trip the pawl 105 into engagement with ratchet 113, whereby the belts 77 and 78 will be driven. It is noted further that the sprocket 52 and cam 55 are driven from the main drive of the cigar machine as for example shaft 100, and the cross feed, for example, the shaft 102 of my construction corresponding to the crank shaft 79 of said Patent 1,740,571, may be driven from the same shaft 100 through a sprocket chain 101 so as to insure their being driven in proper timed relation. For convenience in correlating structure, it is noted that the part 82 of the patent is the same part that is shown at 67a in Fig. 3 and my rake 67b is similarly actuated by a counterweight (not shown) when released by a cam actuated arm (not shown) loosely mounted on the shaft 67 whereon the rake 67b is fastened.

The leaves dropped by the scale pan are guided by the open covers 68 and 68b of the cross feed 76, 77, the leaves being dropped into the broad portion of the filler feeding channel between the rear runs of the belt as shown in Fig. 1. The forward runs of said belt are positioned by the pulleys 87 and 88 closer together than the rear ones and there is a constriction of the stream of filler tobacco to the desired width of the bunch prior to severance of the bunch lengths by the corrugated cutter 78. It will be noted that the

cross feed side belts 77 are provided with rear runs 77a traveling over pulleys 77b and 77c and with forward somewhat narrow runs 77d passing over pulleys 77e, 87 and 88. Compression foot 79a is shown between the runs 77d which is similar in all respects to that disclosed in the Bronander Patent 1,740,571, above referred to. The portion of the stream of filler tobacco underlying the horizontal bottom surface of the compression foot 79a is compressed by the same while the knife 78 severs a bunch length from the leading end of the filler stream T (Fig. 5). Compression foot 79a is suspended from a rod 200 slidably mounted in a lug 202 of the reciprocable plunger 78a. A compression spring 204 interposed between the lug 202 and the compression foot 79a normally holds the nut 206 against the lug 202. The severed bunch length now rests upon the swingable shelf 80 which then descends, whereupon the rake 67b moves to the dotted position shown in Fig. 3 and sweeps the severed bunch length against the rear end of the column C from whose forward end the bunch charge is cut by the cutter 84. The construction of the bunch length cutter and the manner in which the compression foot is supported, is similar to that illustrated in the Carlson Patent 2,247,358.

What is claimed is:

1. In a cigar machine filler feed, the combination with a horizontal belt adapted to support a continuous stream of long filler tobacco wherein the filler tobacco extends lengthwise of the stream, of a pair of endless side belts coacting with said horizontal belt to advance the stream of long filler tobacco, said belts having parallel opposed vertical runs from which the filler stream emerges and parallel opposed vertical runs between which the filler tobacco is deposited, the runs from between which the filler stream emerges being more closely spaced than the runs between which the filler tobacco is deposited, to constrict the filler stream laterally to the desired width, a compactor having a horizontal bottom adapted to engage the portion of the filler stream between said more closely spaced belt runs and compact this portion of the filler stream to a predetermined degree, and a vertical knife for separating bunch lengths from the portion of the filler stream emerging from between said more closely spaced runs.

2. In a cigar machine filler feed, the combination with a horizontal belt adapted to support a continuous stream of long filler tobacco wherein the filler tobacco extends lengthwise of the stream, of a pair of endless side belts coacting with said horizontal belt to advance the stream of long filler tobacco, said belts having parallel opposed vertical runs from which the filler stream emerges and more widely spaced vertical runs between which the filler tobacco is deposited whereby the filler stream is laterally constricted between said more closely spaced runs to the desired width, a compactor having a horizontal bottom adapted to engage the portion of the filler stream between said more closely spaced belt runs and compact the same to a predetermined degree, and a vertical knife for separating bunch lengths from the portion of the filler stream emerging from between said more closely spaced runs.

3. In a cigar machine filler feed, in combination, a pair of traveling endless belts having opposed vertical runs and an endless traveling belt having a horizontal run underlying said vertical runs, said opposed runs and horizontal run form-

ing a filler feed channel wherein a continuous stream of filler tobacco is advanced, the portions of said vertical runs adjacent the end of said channel from which said filler stream emerges being disposed closer to each other than at the other end of said channel to engage the longitudinal edges of said filler stream and constrict the filler stream laterally to a narrower breadth, a vertically movable compactor having a horizontal bottom adapted to engage and compact the portion of the filler stream so constricted adjacent

the outlet end of said channel, and mechanism for separating bunch lengths from the constricted and compacted portion of the filler stream emerging from said channel and assembling the separated bunch lengths side by side in a column, said mechanism including a member for advancing the separated bunch lengths transversely and compacting them laterally against said column.

10

HENRY H. WHEELER.
